TELEPHONE AND LIKE TRANSMISSION
SYSTEMAlan Dower Blumlein, London, England, assignor
to Columbia Phonograph Company, Inc.,
Bridgeport, Conn., a corporation of New YorkApplication April 24, 1930, Serial No. 446,892
In Great Britain June 29, 1929

1 Claim. (Cl. 178—44)

This invention relates to electrical transmission systems with particular reference to amplifiers, sound reproducing systems and telephone transmission lines and the like over which complex frequencies are transmitted.

It is known that in order to correct for, or introduce distortion in magnitude or phase in an electrical transmission system use may be made of networks which are inserted in the system in order to modify the relations between the input currents and output currents at various frequencies. The object of these networks may be (1) to improve the quality of the transmission system by modifying the relative magnitudes and phases of certain frequencies; (2) to cut out or reduce certain frequencies which may not be desired as they introduce noise or overloading; (3) to control the magnitude of the received currents to a desired value; (4) to produce standards of attenuation against which apparatus may be compared; (5) to select certain frequencies for transmission for testing purposes. These networks may also be used to effect economies by correcting for distortion of magnitude and phase produced by systems of transmission, which, though cheap, cannot be used without correction.

The main object of the present invention is to combine efficiency of transmission with economy in the cost of installing the system by reducing the complexity of networks employed while at the same time permitting such networks properly to fulfill their functions.

According to my invention I employ what may be termed a "Half Wheatstone" network which may be arranged to perform any of the functions mentioned. In order that the operation of the present invention may be the more fully understood a description of how a network according to the invention is derived from both a Wheatstone bridge or a phantomed telephone circuit will be given in the following description.

Referring to the drawings which accompanied the provisional specification:—

Figure 1 illustrates a modified form of Wheatstone bridge according to the invention.

Fig. 2 shows a further form.

Fig. 3 represents a telephone phantoming repeating coil group.

Fig. 4 represents a modified arrangement of Fig. 3.

Fig. 5 shows a device similar to Fig. 2.

Fig. 6 represents an arrangement having a uniform transmission and equivalent to Fig. 5.

Fig. 7 illustrates a network according to the invention and designed to have constant charac-

teristic impedances and an attenuation variable with frequency.

Fig. 8 illustrates a network having an imperfect transformer.

Fig. 9 shows a combination of four networks according to the invention, while

Fig. 10 shows a combination of five networks.

Figs. 11 to 14 show further forms of the invention in which a transformer or retardation coil is employed whose tapping point is not central, and

Fig. 15 shows a still further form of the invention.

The equations giving the current in the detecting device of a Wheatstone bridge in terms of the E. M. F. of, or current supplied by, the source are well known. It is also well known that by varying the impedance of the arms of the bridge the current flowing to the detecting device can be varied.

According to the form of the invention shown in Fig. 1 I employ two ratio arms 1 and 2 consisting of two similar windings on a common high permeability magnetic core, while the other two arms of the bridge consist of two impedances Z_A and Z_B . The detector terminals 3 are located across the ratio arms and impedances while the generator terminals 4 are connected to the junctions of the two ratio arms and of the impedances respectively. A modification of the bridge may be employed as shown in Fig. 2 in which the detector terminals 3 are not connected directly to the bridge but are connected to a secondary transformer winding 5 on the same magnetic core as the windings 1 and 2. The generator and detector are of course interchangeable without affecting the bridge balance. If the electrical characteristics of windings 1 and 2 are equal then no current will be obtained at the detector terminals 3 located across the ends of the secondary transformer winding from an alternating source at the generator terminals 4 arranged as before, if the impedance of Z_A is equal to that of Z_B .

If Z_A does not equal Z_B the power will be transmitted through the bridge from the source to the detector. By varying the degree of unbalance of Z_A and Z_B the phase and magnitude of the transmitted currents can be varied at will. Finally by so constructing Z_A and Z_B that their degree of unbalance varies with frequency the bridge may be used to transmit currents with a definite frequency discrimination.

This bridge network may be used as a network for modifying currents transmitted through it from the generator terminals 4 to the detector terminals 3 or vice versa.

Figure 3 represents a telephone phantom repeating coil group having impedances representing the line. Two repeating coils 9 and 10 are provided whose secondaries have accurate centre point tappings from which the phantom connections are taken. Terminals 6 and 7 are provided for each primary winding of the repeating coils of the side (or physical) circuits and terminals 8 for the phantom circuit. Z_A , Z_B , Z'_A , and Z'_B are impedances closing the phantom and side circuits. If $Z_A = Z_B$ then there will be no side to phantom crosstalk between the terminals 6 of one primary winding and the terminals 8 of the phantom circuit, that is to say no power can be transmitted between these terminals, but if however Z_A and Z_B are unbalanced then power can flow between such terminals. If, now the terminals 8 of the phantom circuit are short circuited and a generator applied to terminals 6 and 7, Z_A and Z_B are unbalanced, then current will flow in the phantom circuit. If, then Z'_A and Z'_B are unbalanced this phantom current will cause currents to flow in the second side circuit in an impedance connected to terminals 7. Thus the currents transmitted from terminals 6 and 7 can be modified twice, first by the unbalance of Z_A and Z_B and then by the unbalance of Z'_A and Z'_B .

Fig. 4 shows the circuit above described rearranged with the terminals 8 of the phantom circuit short circuited, whereby power may be transmitted from terminals 6 as side circuit terminals through the unbalance of Z_A and Z_B to the phantom circuit at 11 and back to another side circuit through the unbalance of Z'_A and Z'_B to terminals 7. It will be seen that if the network is divided along the dotted line 11 it is the same as two of the networks shown in Fig. 2.

Having thus described two view points from which the method of operation of the network may be understood some description of the impedance and attenuation characteristics will now be given.

Fig. 5 illustrates a "Half Wheatstone" network according to the invention comprising a primary winding 16 of a transformer and a secondary winding having two balanced halves 17 and 18. This transformer is, for the purpose of the following calculations, assumed to be perfect, within the working frequency range of the device. That is to say, assuming that L_1 , L_2 and M be the inductances of, and mutual between, the windings, then M is assumed very large and

$$(\sqrt{L_1 L_2} - M)$$

is assumed very small, and the resistance of the windings is assumed to be negligible.

Also, the centre point tap 20 of the secondary is assumed to be such that for a current entering at the point 20 and dividing and flowing out equally at ends of the secondary winding 21 and 22 no impedance will be presented to this current and no potential difference will be produced between terminals 12 and 13 of the primary winding or between the ends of the secondary winding 21 and 22. Z' may be assumed to be the impedance looking into terminals 12 and 13 of the primary winding and Z'' the impedance looking into the terminals 14 and 15 connected respectively to the center of the secondary winding and to impedances Z_A and Z_B arranged in series one with each half of the secondary winding. The impedance Z' when the terminals 14 and 15 are short circuited may be written Z'_{sc} , and when on open circuit Z'_{oc} . By

applying Kirchhoff's laws to this network it can be easily shown that $Z'_{oc} = Z_A + Z_B$ and

$$Z'_{sc} = \frac{4Z_A Z_B}{Z_A + Z_B}.$$

The characteristic impedance looking into the terminals 12 and 13 of the primary winding may then be written

$$Z_o' = \sqrt{Z'_{oc} Z'_{sc}} = 2\sqrt{Z_A Z_B} = 2Z_o \quad 10$$

where

$$Z_o = \sqrt{Z_A Z_B}$$

also

$$\tanh \theta = \sqrt{\frac{Z'_{sc}}{Z'_{oc}}} = \sqrt{\frac{4Z_A Z_B}{(Z_A + Z_B)^2}} = \frac{2}{\sqrt{\frac{Z_A}{Z_B}} + \sqrt{\frac{Z_B}{Z_A}}} \quad 15$$

where θ is the transfer or total propagation constant of the network. 20

Similarly the impedances looking in at the terminals of the secondary windings 14 and 15 using the same notation are given by:—

$$Z'_{oc}'' = \frac{Z_A + Z_B}{4} \quad 25$$

$$Z'_{sc}'' = \frac{Z_A \cdot Z_B}{Z_A + Z_B}$$

$$Z''_o = \sqrt{Z'_{oc}'' Z'_{sc}''} = \sqrt{\frac{Z_A Z_B}{4}} = \frac{Z_o}{2} \quad 30$$

and as before

$$\tanh \theta = \sqrt{\frac{Z'_{sc}''}{Z'_{oc}''}} = \frac{2}{\sqrt{\frac{Z_A}{Z_B}} + \sqrt{\frac{Z_B}{Z_A}}} \quad 35$$

It can be shown that if

$$\tanh \theta = \frac{2}{\sqrt{\frac{Z_A}{Z_B}} + \sqrt{\frac{Z_B}{Z_A}}} \quad 40$$

then

$$\theta = \log_e \frac{1 + \sqrt{\frac{Z_A}{Z_B}}}{1 - \sqrt{\frac{Z_A}{Z_B}}} \quad 45$$

The network is therefore equivalent to the arrangement shown in Fig. 6 having a uniform transmission line 24 with impedance

$$Z_o = \sqrt{Z_A Z_B}$$

and total propagation constant given by

$$\theta = \log_e \frac{1 + \sqrt{\frac{Z_A}{Z_B}}}{1 - \sqrt{\frac{Z_A}{Z_B}}} \quad 60$$

and having two ideal transformers 23 and 25 having voltage ratios of

$$\sqrt{2}:1$$

and impedance ratios of 2:1. 65

The characteristic impedances between terminals 12 and 13 of the first transformer and between the terminals 14 and 15 of the second transformer will then as before be given by $Z'_o = 2Z_o$ and $Z''_o = Z_o$. 70

$$Z''_o = \frac{Z_o}{2}$$

By suitably proportioning Z_A and Z_B the net- 75

work may be given a desired impedance and a desired attenuation and phase characteristic. Since

$$5 \quad \theta = \log_e \frac{1 + \sqrt{\frac{Z_A}{Z_B}}}{1 - \sqrt{\frac{Z_A}{Z_B}}}$$

it can be shown that

$$10 \quad \sqrt{\frac{Z_A}{Z_B}} = \frac{e^\theta - 1}{e^\theta + 1} = \tanh \frac{\theta}{2}$$

hence

$$15 \quad Z_A = \sqrt{\frac{Z_A}{Z_B}} \cdot \sqrt{Z_A Z_B} = Z_0 \tanh \frac{\theta}{2}$$

$$Z_B = \frac{\sqrt{Z_A Z_B}}{\sqrt{\frac{Z_A}{Z_B}}} = Z_0 \coth \frac{\theta}{2}$$

20 So the values of Z_A and Z_B may be calculated for any desired values of Z_0 and θ .

This network may be made to perform many functions, a few examples of which are given below.

25 For example Z_A and Z_B may be pure resistances in which case θ will be real and constant with frequency representing a constant attenuation. By arranging a switch to vary the resistances in such a manner that

$$30 \quad \sqrt{Z_A Z_B} = Z_0 = \text{a constant},$$

and

$$\frac{Z_A}{Z_B}$$

35 has various values, a constant impedance variable attenuator may be made.

Further by arranging the switches (or a slide wire) to make

$$\frac{Z_A}{Z_B}$$

40 both greater and less than unity an attenuator may be produced which will give an output current in either sense, i. e. reverse the current direction.

45 Figure 7 shows a network designed to have constant characteristic impedances and an attenuation variable with frequency. One of the arms of the bridge is provided with a resistance R and inductance L in series, while the other arm is provided with a resistance R shunted by a capacity C . The values of L and C are chosen such that

$$55 \quad \sqrt{\frac{L}{C}} = R$$

Putting

$$\omega_1 = \frac{1}{\sqrt{LC}}$$

we get

$$60 \quad Z_A = R + j\omega L = R \left(1 + j\frac{\omega}{\omega_1} \right)$$

$$65 \quad Z_B = \frac{\frac{1}{j\omega C}}{R + \frac{1}{j\omega C}} = \frac{R}{1 + j\frac{\omega}{\omega_1}}$$

$$Z_0 = \sqrt{Z_A Z_B} = R$$

$$70 \quad \theta = \log_e \frac{1 + \sqrt{\frac{Z_A}{Z_B}}}{1 - \sqrt{\frac{Z_A}{Z_B}}} = \log_e \frac{1 + 1 + j\frac{\omega}{\omega_1}}{1 - 1 - j\frac{\omega}{\omega_1}} = \log_e \left(2j\frac{\omega_1}{\omega} - 1 \right) =$$

$$75 \quad \frac{1}{2} \log_e \left\{ 4 \left(\frac{\omega_1}{\omega} \right)^2 + 1 \right\} + j \tan^{-1} \left(-\frac{2\omega_1}{\omega} \right)$$

It will therefore be seen that as the frequency is changed from 0 to ∞ the attenuation decreases from ∞ to 0 and the phase constant changes from

$$\frac{\pi}{2} \text{ to } \pi.$$

5

The arrangement is therefore a network of constant characteristic impedance and attenuation varying with frequency. By making Z_A and Z_B of other arrangements of resistances inductances and condensers, other types of variation of attenuation and phase constant with frequency can be obtained with and without constant impedances. It is also possible to produce variable attenuation networks having the impedance varying in a desired fashion.

Suppose Z_A consists of an inductance L and Z_B of a capacity C the impedance will be constant,

$$20 \quad Z_0 = \sqrt{\frac{L}{C}}$$

The ratio

$$25 \quad \sqrt{\frac{Z_A}{Z_B}}$$

will be equal to

$$\sqrt{j\omega L \cdot j\omega C} = j\omega \sqrt{LC}.$$

This gives a value of propagation constant given by

$$30 \quad \theta = j2 \tan^{-1} \omega \sqrt{LC}.$$

Then this network has constant impedance, no attenuation and a phase constant changing from 0 to 2π as frequency increases from 0 to ∞ . A network of this type may therefore be used for correcting phase relations in a system. More complicated types may of course be made using combinations of inductances, condensers, and resistances for the two arms.

35 If Z_A is composed of an inductance L and capacity C in series, and Z_B of an inductance L , a network is produced having no attenuation for frequencies below a certain limit. In this case

$$40 \quad Z_A = j\omega L + \frac{1}{j\omega C} \text{ and } Z_B = j\omega L.$$

Writing

$$45 \quad \omega_1 = \frac{1}{\sqrt{LC}}$$

we get

$$50 \quad \sqrt{\frac{Z_A}{Z_B}} = \sqrt{1 + \frac{1}{j\omega C \cdot j\omega L}} = \sqrt{1 - \frac{\omega_1^2}{\omega^2}}$$

and

$$55 \quad \theta = \log_e \frac{1 + \sqrt{1 - \frac{\omega_1^2}{\omega^2}}}{1 - \sqrt{1 - \frac{\omega_1^2}{\omega^2}}}$$

When

$$60 \quad \omega < \omega_1 \left(\text{i. e. } \frac{\omega_1^2}{\omega^2} > 1 \right)$$

$$65 \quad \theta = 2j \tan^{-1} \sqrt{\frac{\omega_1^2}{\omega^2} - 1}$$

When

$$70 \quad \omega > \omega_1 \left(\text{i. e. } \frac{\omega_1^2}{\omega^2} < 1 \right)$$

$$75 \quad \theta = \log_e \frac{1 + \sqrt{1 - \frac{\omega_1^2}{\omega^2}}}{1 - \sqrt{1 - \frac{\omega_1^2}{\omega^2}}} + j \cdot o.$$

That is to say that when $\omega < \omega_1$ the network has

no attenuation but only a phase constant but when $\omega > \omega_1$ the network gives attenuation without phase shift, in fact the network is acting as a low pass filter. The impedance of this network is not constant, being given by

$$Z_0 = \sqrt{\frac{L}{C}} \sqrt{1 - \frac{\omega^2}{\omega_1^2}}$$

- 10 For frequencies below cut off frequency ($\omega < \omega_1$) this impedance is resistive and for low frequencies approximates to

$$\sqrt{\frac{L}{C}}$$

- 15 Above cut off the impedance is reactive. As before by suitably arranging the composition of Z_A and Z_B filters of various types may be produced.

- 20 In considering this network so far it has been assumed that the transformer is ideal. It can be shown that if the transformer is not ideal, though well balanced about its center point tapping, the network is equivalent to that shown in Fig. 8, comprising a half Wheatstone network 25 27 having an ideal transformer, in circuit with an imperfect transformer 26 similar to that actually employed in the network though no use is made of the center tapping 29. This transformer is connected to the high impedance side of the network. 28 represents an impedance Z_0 which is equal to the impedance presented by the transformer secondary to the flow of current from the center tapping 29 of the secondary winding 30 dividing equally and leaving by terminals 30 and 31 of the winding. Z_0 is in fact the impedance of the two halves of the secondary winding connected in parallel opposing. This arrangement is then identically equivalent to a half Wheatstone network shown in Fig. 5 having an imperfect transformer. The network 27 representing a network having an ideal transformer may as before be replaced by the network as shown in Fig. 6 without altering the characteristics.

- 45 If an imperfect retardation coil is employed instead of a transformer in the network, this network may be represented by an arrangement similar to that shown in Fig. 8 except that the transformer 26 is replaced by the imperfect retardation coil and the impedance Z_0 is the impedance of the two retardation coil windings in parallel opposing.

- 55 In order to obtain a good balance on the transformer or retardation coil and at the same time reduce the value of Z_0 to a minimum it is advantageous to wind the two balanced halves as tightly coupled as possible; for example, intermeshed or bifilar windings may be used similar to those usually employed for the line windings 60 of telephone repeating coils where an accurate central phantom tapping is required. In order to balance the capacities of the coil it may be advantageous to use an electrostatically shielded transformer or to earth the center point tapping.

- 65 If tightly coupled windings are used for the two balanced halves of the coil the impedance Z_0 will be practically a pure resistance. In this case if the impedance of the network is resistive, a shunt resistance and further series resistance 70 may be added in order that Z_0 may become one arm of a T network of impedance

$$\frac{Z_0}{2}$$

- 75 giving a constant attenuation invariant with fre-

quency. The impedance at terminals 14 and 15, Figure 8, will then be exactly

$$\frac{Z_0}{2}$$

Similarly if a similar type of network is to be inserted at 14 and 15 so that in effect two resistances Z_p are obtained in series, a single shunt resistance may be placed across the terminals in order that this shunt resistance together with the two series resistances Z_p may form a constant attenuation T network of constant impedance

$$\frac{Z_0}{2}$$

Such resistance is shown at 40, Fig. 9. Although this resistance increases the attenuation it makes the impedance conditions correct at this junction even though imperfect transformers are used.

If it is desired to obtain equal impedances at each end of a single section of this network a 2:1 impedance ratio transformer may be used. Similarly any ratio may be used to obtain a desired impedance at the end of the network.

A number of these networks may be connected together in order that their attenuative effects may add together. Fig. 9 shows four sections of network may be employed connected in succession and having three transformers. By making Z_0 the same for each of the networks the attenuations of the networks will add directly. The impedance at the terminals 36 and 37 of the primary of one transformer, between sections 33 and 34, and at the terminals 38 and 39 of the last transformer will be $2Z_0$. The impedance between sections 32 and 33 and between sections 34 and 35 will be

$$\frac{Z_0}{2}$$

As has been stated before a resistance 40 is inserted to correct the error in impedance relations introduced between sections 34 and 35 by the parallel opposing impedances of the two halves of the tapped transformer windings. The effect of this is to introduce a constant loss independent of frequency.

A more complex method of coupling is employed where five sections of network are utilized, as illustrated in Fig. 10. The network comprises five sections 41, 42, 43, 44, and 45 having terminals 46 and 47. In order to make the impedance relations correct

$$Z_A Z_B = Z' A Z' B = Z'' A Z'' B = Z' A Z'' B = Z_0$$

The characteristic impedance at the terminals 46 of the first section will then be

$$\frac{Z_0}{2}$$

and at the terminals 41 of the last section

$$\frac{Z_0}{8}$$

Section 41 is coupled to section 42 by means of a transformer with a 2:1 voltage ratio and 4:1 impedance ratio. Section 42 is coupled to section 43 by means of a single retardation coil with central tapping. Section 43 is coupled to section 44 by means of a retardation coil so arranged as to give the correct 1:4 impedance ratio. It must be noted that the attenuation produced by sec-

70

75

tions 42, 43 and 44 must be low, in order that the direct coupling produced between the input of 42 and the output of 44 by the parallel opposing impedance of the retardation coils shall be negligible in effect.

Section 44 is coupled to section 45 by means of a retardation coil. Due to the method of coupling it is necessary that

$$Z'''_A Z''_B = 16 Z''''_A Z'''_B. \quad 10$$

An earth connection is provided in section 43 at 48 and it will be seen that the coupling between sections 43 and 44 is such that both input and output leads of section 44 have one side at ground potential. Such coupling might be used between the anode of a three electrode vacuum tube and the grid of a successive tube.

Many other arrangements of these networks in succession can be devised, and these networks 20 may also be joined in series with networks of other well-known types.

In order that this network may be as effective as possible it is necessary that the transformer or retardation coil used should be as nearly 25 ideal as possible. It is especially important that the loss introduced by the transformer should be constant throughout the working range of the device, or this variation of attenuation will be added to the attenuation variation with frequency of the network.

Any improvements in transformer design which 35 improve the impedance relations seen through the transformers and decrease the variation of loss with frequency will improve the device, so also will any improvements which reduce the impedance of the two balanced windings in parallel opposing. Improvements in the balance of the transformer or retardation coil will improve the operation of the device at high attenuations.

Another possibility arises in the use of a transformer or retardation coil whose tapping point is not central. This tapping point may be moved slightly from center in order to allow for small manufacturing errors in the constituents of the 45 two impedance arms.

This type of network may also be made having unequal ratio arms, that is to say when the tapping point of the transformer is not central. The two windings forming the secondary or retardation coil are then wound with the turns in a definite ratio, not being unity. The ratio, assuming the two windings to be perfectly tight coupled, would be proportional to the number of turns. Figs. 11 and 12 show such a network having a positive value of n , which is the ratio of the coil winding turns. Fig. 11 represents the arrangement employing a retardation coil, and Fig. 12 and arrangement employing a transformer. Furthermore, the ratio n may have negative value 50 as shown in Figs. 13 and 14 and may be given by either a retardation coil, Fig. 13 or a transformer, Fig. 14. In such cases the ratio windings approximate to perfectly tight coupled windings having n times the number of turns between the terminals 55 49 and 50 of one coil as there are between the terminals 50 and 51 of the other coil.

The windings are connected so as to give an inductive series aiding connection when connected as shown. When a transformer is used, as 60 shown in Figs. 12 and 14, it is assumed, for the formulae which follow, that the primary winding 5 has the same number of turns as there are between the two points 49 and 51. The arm impedances in the network are taken as Z_A and $n Z_B$ 65 so that the bridge is balanced when $Z_A = Z_B$.

For these networks the characteristic impedance Z_0 looking in at the terminals 3 of the primary is given by

$$Z_0' = (n+1) \sqrt{Z_A Z_B} \sqrt{\frac{Z_A + n Z_B}{n Z_A + Z_B}} \quad 5$$

and the characteristic impedance Z_0'' looking into the terminals 4 from the tapped secondary and the impedances is given by

$$Z_0'' = \frac{n}{n+1} \sqrt{Z_A Z_B} \sqrt{\frac{n Z_A + Z_B}{Z_A + n Z_B}} \quad 10$$

The propagation constant is given by

$$\theta = \tanh^{-1}(n+1) \sqrt{\frac{Z_A Z_B}{(n Z_A + Z_B)(Z_A + n Z_B)}} \quad 15$$

It will be seen that when $Z_A = Z_B$, $\tanh^{-1} \theta = 1$, that is to say the attenuation is infinite.

The expression for θ may be re-written by 20 putting $n Z_B = Z_c$ where Z_c is the impedance in the arm.

$$\theta = \tanh^{-1}(n+1) \sqrt{\frac{Z_A Z_c}{(n^2 Z_A + Z_c)(Z_A + Z_c)}} \quad 25$$

For example suppose Z_A is an inductance L and Z_c is a capacity C such that

$$\omega_1 = \frac{1}{\sqrt{LC}} \quad 30$$

θ is then given by:

$$\theta = \tanh^{-1} \frac{j(n+1) \frac{\omega_1}{\omega}}{\sqrt{\left(\frac{n^2 - \omega_1^2}{\omega^2}\right) \left(1 - \frac{\omega_1^2}{\omega^2}\right)}} \quad 35$$

It will be seen that when

$$\omega^2 < \frac{\omega_1^2}{n^2} \text{ or } \omega^2 > \omega_1^2 \quad 40$$

there will be no attenuation since $\tanh \theta$ will be imaginary and so θ imaginary. Also when

$$\omega_1^2 > \omega^2 > \frac{\omega_1^2}{n^2} \quad 45$$

there will be attenuation since $\tanh \theta$ will be real and so θ real.

If n is negative there will be a frequency of infinite attenuation when

$$\omega^2 = -\frac{\omega_1^2}{n} \quad 50$$

A further method of using the network with 55 equal ratio arms consists of interchanging the network impedance and the input and output terminals. Such an arrangement is shown in Fig. 15. The two network impedances are shown as $2Z_A$ bridged across the transformer secondary 60 52 and

$$\frac{Z_B}{2}$$

between the center point of the transformer primary 53 and the common point 54 of the input and output terminals. 55 and 56 represent the input and output terminals.

It can be shown that Z_0 the characteristic impedance of terminals 55 or terminals 56 is given 70 by

$$Z_0' = \sqrt{Z_A Z_B} = Z_0$$

and similarly

$$Z_0'' = \sqrt{Z_A Z_B} = Z_0 \quad 75$$

As for the network shown in Fig. 5

$$\tanh \theta = \frac{2}{\sqrt{\frac{Z_A}{Z_B}} + \sqrt{\frac{Z_B}{Z_A}}}$$

5 and

$$\theta = \log \frac{1 + \sqrt{\frac{Z_A}{Z_B}}}{1 - \sqrt{\frac{Z_A}{Z_B}}}$$

10

This network is therefore similar in characteristics to that already described except that the input and output impedances are both equal 15 to Z_0 .

The invention may clearly be applied to the design of mechanical analogues of the various electrical circuits herein described.

It will be understood that the foregoing details are given purely by way of illustration and not of limitation since the nature of the invention only is herein indicated and I may vary the number of networks employed, the manner in which the respective impedances are obtained

and the values of the inductances, resistances and capacities adopted depending upon the purpose for which the network is to be employed or any practical requirements that may have to be fulfilled.

Having now particularly described and ascertained the nature of my said invention and in what manner the same is to be performed, I declare that what I claim is:—

An electrical transmission net-work, comprising two inductive windings tightly coupled to each other and two impedances, said inductances and impedances being adjacent each other and being connected to form a bridge, a pair of terminals connected to the junction point of said impedances and to the junction point of said inductances, another pair of terminals connected to the extreme ends of said inductances and a resistance shunt connected across said first-named pair of terminals to correct the impedance change 15 introduced by the parallel inductive opposing impedance of the magnetically coupled arms.

ALAN DOWER BLUMLEIN.
